UNITED STATES PATENT OFFICE

ROBERT BEHRENDT, OF ALTOONA, PENNSYLVANIA

KEYHOLE PROTECTOR

Application filed May 31, 1930. Serial No. 458,270.

This invention relates to improvements in protecting devices, particularly to a key-hole protector, and it is the principal object of my invention to provide such a protector adapted to be readily attached over a key-hole to close the same against peepers, etc., and to prevent its removal from the outside by the insertion of a key, or other means.

Another object of my invention is the provision of a key-hole protector of comparatively simple and inexpensive construction, yet durable and efficient in its operation.

A further object of my invention is the provision of a key-hole protector equipped with means for locking the protector in its key-hole protecting position.

A still further object of my invention is the provision of a key-hole protector comprising a spring controlled rotary member carrying a latch adapted to enter a key-hole and upon its rotation for 90° to hold the protector in its operative position.

These and other objects and advantages of my invention will become more fully known as the description thereof proceeds, and will then be specifically defined in the appended claims.

In the accompanying drawings forming a material part of this disclosure:

Fig. 1 is an inner front elevation of a door equipped with a key-hole protector constructed according to my invention.

Fig. 2 is a fragmentary sectional side-elevation of a door lock with the key-hole protector in position thereon, on a somewhat enlarged scale.

Fig. 3 is a fragmentary front elevation of a door lock on an enlarged scale with the key-hole protector in position to protect the key-hole.

Fig. 4 is a longitudinal section through the key-hole protector.

Fig. 5 is an inner end view of the key-hole protector.

As illustrated, the key-hole protector comprises a rubber protecting cup 10 which has formed therewith a cylinder 11 into which telescopes a rotary member 12, circular in cross-section and carrying an outer head or operating knob 13.

Integrally made with member 12 and centrally located therein is a rod 14 extending through member 12, cylinder 11 into cup 10 where it carries a latch 15.

A spring 20 is wound about rod 14 within the cylinder 11 and rests at one end against the inner end of member 12 while its other end rests against the bottom plate 16 of cylinder 11.

The device operates as follows:

If it is desired to protect a key-hole of a lock 17 against a peeper or insertion of a key, the cup 10 is firmly pressed against the front plate 18 of the lock, and the member 12 is then pressed inwardly by means of its knob and turned for 90°, the latch 15 will assume the position shown in Figure 3 behind the key-hole 19 and will be held in this position by the spring 20, and thus prevent the removal of the key-hole protector by pushing it out of its protective position from the outside of the door and by inserting a key.

It will be understood that I have described and shown the preferred form of my device only, and that I may make such changes in its construction as come within the scope of the appended claims without departure from my invention.

Having thus described my invention what I claim as new and desire to secure by Letters Patent is:

1. A key-hole protector comprising a protecting cup adapted to be secured over a key-hole, a cylinder formed therewith, a rotary member telescoping into said cylinder, an operating knob on said member, a rod formed with said member extending through said cylinder into said cup, a latch at the end of said rod within said cup, and a spring wound about said rod within said cylinder adapted to be tensioned upon the inward movement of said member and locking by its expansion said latch upon its rotation by said member into locking position in such position.

2. A key hole protector of the class described, comprising a cylinder, a bottom plate formed with said cylinder, a rubber cup adapted to engage the key-hole plate in which said bottom plate is enclosed, a rotary member

telescoping into said cylinder, a rod integral with said member extending through the same, the cylinder and the cup into the key hole, a latch carried by the outer end of said rod, a spring wound about the rod part within said cylinder resting at one end against said member and at its opposite end against the bottom plate of the cylinder, and an operating knob on said member and rod allowing a rotation of said latch to bring the latch into position for protecting the key-hole against insertion of a key, and removal of the protector.

10 In witness whereof I have signed my name
15 to this specification.

ROBERT BEHRENDT.
